(57) **CLAIM**

The ornamental design for a tension balancing stop bar, as shown and described.

DESCRIPTION

FIG. 1 is a perspective view of a tension balancing stop bar in its environment;

FIG. 2 is a perspective view of the tension balancing stop bar;

FIG. 3 is a top view of the tension balancing stop bar;

FIG. 4 is a bottom view of the tension balancing stop bar;

FIG. 5 is a rear view of the tension balancing stop bar;

FIG. 6 is a front view of the tension balancing stop bar;

FIG. 7 is a right side view of the tension balancing stop bar; and,

FIG. 8 is a left side view of the tension balancing stop bar. The broken lines of the tension balancing stop bar are for the purpose of illustrating environmental structure and form no part of the claimed design.
